UNITED STATES PATENT OFFICE

132,936

DESIGN FOR A COMBINED LIPSTICK COVER AND MIRROR

Henry Pommier, New York, N. Y.

Application June 4, 1942, Serial No. 107,116

Term of patent 3½ years

To all whom it may concern:

Be it known that I, Henry Pommier, a citizen of no country, residing in New York city, county of New York, and State of New York, have invented a new, original, and ornamental Design for a Combined Lipstick Cover and Mirror, of which the following is a specification, reference being had to the accompanying drawing, forming part thereof.

Fig. 1 is a front perspective view of a combined lipstick cover and mirror showing my new design.

Fig. 2 is a side perspective view thereof.

I claim:

The ornamental design for a combined lipstick cover and mirror, substantially as shown.

HENRY POMMIER.
